UNITED STATES PATENT OFFICE.

JOHN SAUNDERS, OF LOS ANGELES, CALIFORNIA, ASSIGNOR TO SMITH & MARSH INCORPORATED, OF LOS ANGELES, CALIFORNIA, A CORPORATION OF CALIFORNIA.

METHOD AND APPARATUS FOR PRODUCING DAIS AND SUNK-DAIS EMBOSSED.

1,243,226.

Specification of Letters Patent. Patented Oct. 16, 1917.

Application filed May 22, 1916. Serial No. 99,237.

To all whom it may concern:

Be it known that I, JOHN SAUNDERS, a citizen of the United States, residing at Los Angeles, in the county of Los Angeles and State of California, have invented a new and useful Method and Apparatus for Producing Dais and Sunk-Dais Embossing, of which the following is a specification.

My invention relates to the engraver's art, and the principal object of my invention is to provide a method and apparatus by which various forms of embossing may be impressed upon paper or the like and by which words or other symbols may be printed on the embossed portion or on the background from which the embossed portion is raised.

In my invention, I provide a die which raises a portion of the paper to an embossed plane, in combination with means for printing words or symbols either on the embossed plane or on the original plane of the paper.

Referring to the drawings, which are for illustrative purposes only:

Figure 1 is a front view of a piece of paper on which an embossed design has been produced by my method.

Fig. 2 is a section through said paper, and

Fig. 3 is the die by means of which the embossing has been done.

Fig. 4 is a more ornate design in which both a raised and sunk dais appear.

Fig. 5 is a section through the paper of Fig. 4, on the line x^5-x^5 of Fig. 4.

Fig. 6 is a section through the die, by means of which the impression is produced.

Referring to the modification of the invention shown in Figs. 1, 2 and 3, it will be seen that letters 11 are formed on the original plane of the paper 10, said letters 11 appearing on this plane and a raised dais 12 being shown above the plane of the paper 10 on which letters 13 appear. The design is produced by means of the die shown in Fig.

3 in which 14 is a die and 15 is a removable facing of sheet brass, sheet steel, or any such material. The die 14 has the letters 13 engraved thereon as shown at 16, and the removable facing has a dais opening 17 corresponding to the raised dais 12. Engraved

on the facing 15, as shown at 18, are the letters 11. The letters 11 and the letters 13 may appear in the same color, or in different colors, or one or both may be impressed on the paper without being colored. If it is desired to produce the design in two colors, for example, to have the letters 11 red, and the letters 13 blue, the operator proceeds as follows:

The facing 15 is removed from the die 14 and the engraved spaces 16 are inked in blue ink and wiped in accordance with the regular manner of producing engraved designs. The facing 15 is then placed on the die 14 and held in place by a turned-down flange, and the engraving 18 is inked in red, and the die 14 wiped. A single stroke of the press will then produce the design as shown in Fig. 1, with the letters 11 in red and the letters 13 in blue.

As far as I am aware this is the only method by which multi-colored embossed designs may be produced with one stroke of the press. If it is desired to use the same color of ink in both designs, exactly the same process is used, except that the same color of ink is used in the engraving 18 as is used in the engraving 16.

The great advantage of the removable facing 15 is that it enables the engraving 16, which is to produce the letters 13, to be inked and wiped as in the usual way. If the facing 15 were an integral part of the die 14, it would be impossible to ink the engraving 16 without getting ink into the corners of the depression 17. It would also be difficult, or impossible, to use two colors, as may be used in my invention as described above.

In the form of my invention illustrated in Fig. 4, the original plane of the paper 20 is provided with a raised dais 21 and with a sunk dais 22, certain markings 23 appearing on the plane of the paper, certain letters 24 appearing on the raised dais, and certain markings 25 appearing on the sunk dais. In the means illustrated in Fig. 6 for producing this result, a die 26 is supplied with an outer removable facing 27 and a removable sunk dais member 28. The die 26 is

engraved, as shown at 29, to produce the letters 24, the removable facing 27 is engraved as shown at 30 to produce the markings 23, and the removable member 28 is 5 engraved as shown at 31 to produce the markings 25. The central portion 28 may be secured in the die by means of a pin 32, or by the usual waxed card-board used by embossers, or by any other convenient means.

10 The method of operating the form of the invention shown in Figs. 4, 5 and 6 is as follows:

The facing 27 and the removable member 28 are removed from the die 26 and the 15 engraving 29 is inked in any color desired. The facing 27 is then put in place and the engraving 30 is inked in the same or any other color, and the member 28 is put in place and the engraving 31 is inked in any 20 other color desired. A single stroke of the press will then produce the raised design, shown in Fig. 4, in which the letters 24, markings 25 and the markings 23 all appear in different colors, or in the same color, or 25 some or all of them may appear as embossed letters without color.

Other modifications of my invention will be evident to anyone skilled in the art, as, for example, a second facing may be placed 30 over the first facing for the purpose of producing an additional plane on which further engraving may be cut, if desired.

I claim as my invention:—

1. An apparatus for producing dais embossing on paper or the like comprising a die, and a facing for said die detachably secured thereto, said facing being cut away to form a dais opening through which said die may come in contact with said paper.

40 2. An apparatus for producing dais embossing on paper or the like comprising a die, having engraved characters thereon, and a facing for said die detachably secured thereto, said facing being cut away to form 45 a dais opening through which the engraved characters on said die may come in contact with said paper.

3. An apparatus for producing dais embossing on paper or the like comprising a die, and a removable facing for said die, said facing being cut away to form a dais opening through which said die may come in contact with said paper, said facing having 50 engraved characters thereon.

55 4. An apparatus for producing dais embossing on paper or the like comprising a die having engraved characters thereon, and a removable facing for said die, said facing being cut away to form a dais opening 60 through which the engraved characters on said die may come in contact with said paper, said facing having engraved characters thereon.

60 5. An apparatus for producing dais em-

bossing on paper or the like comprising a 65 die, a facing for said die detachably secured thereto, said facing being cut away to form a dais opening through which said die may come in contact with said paper, and a sunk dais member secured to said die in said dais 70 opening of said facing.

6. An apparatus for producing dais embossing on paper or the like comprising a die having engraved characters thereon, a facing for said die detachably secured thereto, said facing being cut away to form a dais opening through which the engraved characters on said die may come in contact with said paper, and a sunk dais member secured to said die in said dais opening of said facing.

7. An apparatus for producing dais embossing on paper or the like comprising a die, a removable facing for said die, said facing being cut away to form a dais opening through which said die may come in contact with said paper, said facing having engraved characters thereon, and a sunk dais member secured to said die in said dais opening of said facing.

90 8. An apparatus for producing dais embossing on paper or the like comprising a die having engraved characters thereon, a removable facing for said die, said facing being cut away to form a dais opening 85 through which the engraved characters on said die may come in contact with said paper, said facing having engraved characters thereon, and a sunk dais member secured to said die in said dais opening of said facing.

95 9. An apparatus for producing dais embossing on paper or the like comprising a die, a facing for said die detachably secured thereto, said facing being cut away to form 100 a dais opening through which said die may come in contact with said paper, and a sunk dais member secured to said die in said dais opening of said facing.

105 10. An apparatus for producing dais embossing on paper or the like comprising a die having engraved characters thereon, a facing for said die detachably secured thereto, said facing being cut away to form 110 a dais opening through which the engraved characters on said die may come in contact with said paper, and a sunk dais member secured to said die in said dais opening of said facing, said sunk dais member having engraved characters thereon.

115 11. An apparatus for producing dais embossing on paper or the like comprising a die, a removable facing for said die, said facing being cut away to form a dais opening 120 through which said die may come in contact with said paper, said facing having engraved characters thereon.

125 12. An apparatus for producing dais embossing on paper or the like comprising a die, a removable facing for said die, said facing being cut away to form a dais opening through which said die may come in contact with said paper, said facing having engraved characters thereon, and a sunk

dais member secured to said die in said dais opening of said facing, said sunk dais member having engraved characters thereon.

12. An apparatus for producing dais embossing on paper or the like comprising a die having engraved characters thereon, a removable facing for said die, said facing being cut away to form a dais opening through which the engraved characters on 10 said die may come in contact with said

paper, said facing having engraved characters thereon, and a sunk dais member secured to said die in said dais opening of said facing, said sunk dais member having engraved characters thereon.

15

In testimony whereof, I have hereunto set my hand at Los Angeles, California, this 10th day of May, 1916.

JOHN SAUNDERS.
